UNITED STATES PATENT OFFICE.

WINSLOW F. SAMPSON, OF GOFFSTOWN, ASSIGNOR, BY DIRECT AND MESNE ASSIGNMENTS, TO THE SAMPSON AUTOMATIC HEEL BURNISHING MACHINE COMPANY, OF MANCHESTER, NEW HAMPSHIRE.

HEEL-BURNISHING MACHINE.

SPECIFICATION forming part of Letters Patent No. 444,021, dated January 6, 1891.

Application filed August 12, 1889. Serial No. 320,524. (No model.)

To all whom it may concern:

Be it known that I, WINSLOW F. SAMPSON, a citizen of the United States of America, and a resident of Goffstown, in the county of Hillsborough and state of New Hampshire, have invented certain new and useful Improvements in Heel-Burnishing Machines, of which the following is a full, clear, and exact description.

- 10 The machine of this invention consists, essentially, first, of a reciprocating rotating carrier for a boot or shoe, adapted to clamp thereto the boot or shoe at its heel, and so as to have the edge of the heel exposed and to have the heel eccentric to the axis of rotation thereof; second, of a continuously-rotating burnisher in position to bear on the exposed edge of the heel clamped and revolving as stated; third, of a frame at one end supporting the burnisher and at its opposite end adapted to swing and to be moved on a fixed support, and also to hold the burnisher with an elastic and yielding pressure at a bearing on the edge of the clamped heel, and all so that the burnisher can automatically move inward and outward from the axis of rotation of said carrier for the boot or shoe, and also can be moved to and fro across the edge and between the treading-face of the heel and the upper of the boot or shoe; fourth, of means for moving said swinging frame which carries the burnisher forward and backward on its support, and thereby to move it and through it the burnisher to and fro across the edge and between the treading-face of the heel and the upper of the boot or shoe; fifth, of means arranged on said swinging frame carrying the burnisher and connected with the burnisher for rotating it, and which consists, in substance, of a pulley-wheel of the burnisher, pulley-wheels in two pairs and each pair arranged for separate and independent rotation on said frame, and a belt common to one pulley-wheel of both of said pairs of pulley-wheels and leading therefrom to the pulley-wheel of the burnisher, and all so that with said pairs of pulley-wheels suitably driven in opposite directions by then shifting said driving-belt for the burnisher from one to the other of its

driving pulley-wheel of said pair of wheels 50 the rotation of the burnisher can be changed from one to another and opposite direction; sixth, of means for automatically shifting said driving-belt for the burnisher from one to the other of said driving pulley-wheels for said 55 belt, and, seventh, of means for placing the burnisher into and holding it in operative position on the edge of the clamped heel, in combination with means for automatically releasing said holding mechanism for the burnisher, and thereby, under the reaction of its spring-pressure, heretofore referred to, on the burnisher, secure a removal of the burnisher from its operative position, and also at the same time secure an automatic stop of the 60 running of the machine in all its moving parts, except as to those parts through which the burnisher is rotated, as has been explained.

The several essentials of the machine as above specially recited, except that of rotation of the burnisher, are respectively constructed and otherwise arranged and combined in one machine, in substance, so that during one complete rotation of a common driving gear-wheel the clamped heel and in 70 contact with the burnisher will be revolved for the whole length of its edge to be burnished first in one direction and then in the opposite direction. The burnisher while the heel is revolving in one direction will be rotated in one and a proper direction therefor, and while the heel is revolving in the other direction will be rotated in the other and opposite and a proper direction, and at the same time during each direction of its rotation it 75 will be moved frequently to and fro across the edge and between the treading-face of the heel and the upper, and the burnisher will be placed out of its operative position on the heel-edge and the machine will be stopped 80 to be again placed in running connection and the burnisher in operative position on the heel-edge, all substantially as hereinafter described.

In the drawings forming part of this specification, the present improved machine for burnishing the edges of heels of boots and shoes is illustrated.

Figure 1 is a plan view. Fig. 2 is a front elevation. Fig. 2^a is a view in detail, hereinafter referred to. Figs. 3 and 4 are elevations at opposite ends. Fig. 5 is a view in detail, as hereinafter appears. Fig. 6 is a detail view, hereinafter referred to.

In the drawings, A represents the horizontal bed of the machine, to be supported (not shown) in any suitable manner.

- 10 B is the driving-shaft. This shaft is horizontal, and it is under the rear portion, and extends from end to end, and is supported and turns in suitable fixed depending bearing-blocks A² A² of the bed A.
- 15 B' B² are fixed and loose driving pulley-wheels at the end portion of the shaft B, projecting beyond the right-hand end of the bed, and B³ is a vertical pinion gear-wheel fixed on the other projecting end portion of said shaft. The pinion B³ is at the rear of and meshes with a vertical gear-wheel B⁴, held and turning on a fixed horizontal stud B⁵ of the bearing-block A² for the shaft B, which is at the left-hand end of the bed. The gear-wheel B⁴ has a radial slot B⁶, at which by headed screw-bolt and screw-nut B⁷ pivot-connection is made of one end of a pitman-rod B⁸, which at its other end is pivoted and connected to the lower end of a vertical arm B⁹, intermediate fulcrumed and hung on a fixed horizontal stud A³ of a post or upright A⁴ at the front side and left-hand end of the bed and at its upper end portion having a segmental gear B¹⁰, concentric with the axis of stud A³.

- 20 C is a vertical pinion gear-wheel at upper side of and meshing with segmental gear B¹⁰ and fixed on the left-hand end portion of a horizontal shaft C², turning in bearings of the upper end of the post A⁴, and extending therefrom toward the right-hand end of the bed A, and at its said end portion it is offset, as at C³, to one side of its axial line, which line is in the vertical plane of the axial line of the fulcrum-stud A³, and also of pivot-connection of arm B⁹ with pitman-rod B⁸, when the arm and rod are in their normal position, Fig. 1. The offset C³ of shaft C² has an outer end face C⁴ at right angles to its axis for the rest of 25 the boot or shoe (not shown, but placed upon and over said offset) at the inner surface of the heel portion of its sole, and which is held to its said rest by the pressure of a stiff spring-arm C⁵, having a plate C⁶ that bears on the treading-face of the heel and is at the free end of said arm. The opposite end of the 30 spring-arm is rigidly held on a radial arm C⁷ of the shaft C², and the arm C⁵ between its ends has a bow or curving shape, not only to 35 accommodate the boot or shoe when placed between it and the shaft, as above explained, but also to increase its spring and holding pressure.

- 35 The mechanism described constitutes of the machine of this invention the means for holding a boot or shoe with the edge of its heel which is to be burnished exposed and the

means for a reciprocating revolution of the heel so held about the axis of the shaft C² holding the boot or shoe between the opposite inner sole and outer treading-faces of its heel, as has been explained. The reciprocation of the boot or shoe is secured from the continuous rotation of the driving-shaft B, working through the pitman-rod connection B⁸ of it with the vertical arm B⁹, having the segmental gear B¹⁰ in mesh with the wheel C of the shaft C², carrying the boot or shoe, as explained.

40 By adjusting the pivot-connection of pitman-rod B⁸ with the driving gear-wheel B⁴ at a greater or less distance from the center of rotation of said wheel the length of reciprocation of boot or shoe heel can be made more or less, as may be required or desired to suit 45 heels of greater or less length of edge-periphery between the opposite ends of the breast of the heel.

45 D is the burnishing-tool. As particularly shown, this tool D is a vertical wheel having 50 a semicircular convex edge and otherwise formed or constructed as well known for burnishing purposes. The burnisher D in operation is at the upper side of the boot or shoe heel held, as above explained, and it is fixed 55 on one end of a horizontal shaft D², having its axis parallel to the axis of the shaft C², carrying the heel, and turning at opposite end portions in bearings D³ of one end of the frame D⁴, the opposite end D⁵ of which is of 60 a fork shape and is hung to swing through a vertical plane on a horizontal rod D⁶, suspended at its opposite end portions on and extending across and between and free to be moved, as hereinafter appears, lengthwise 65 through the upper ends of the upper and forked arms A⁵ of a fixed vertical post A⁷ at the rear side of the bed A. The axial line of the rod D⁶ is in a vertical plane parallel to the vertical plane of the shaft C², carrying 70 the boot or shoe, and a plane toward the rear of the bed. The frame D⁴, carrying the burnisher D, in its normal position is substantially horizontal, and intermediate of its length it rests on an adjustable screw-collar E of a 75 vertical screw-threaded rod E², which passes upward through a suitable guide-hole (not shown) of the frame D⁴, and at its lower end is pivoted to a horizontal lever-arm E³, located under said frame D⁴, and between it 80 and the bed and at its rear end fulcrumed on a fixed pin A⁸ of the post A⁷ of the bed, at its forward end having a handle E⁴ for convenience in operating it, and between its ends 85 normally engaged and held against upward movement by a latch-catching mechanism, particularly shown in detail, and enlarged, Fig. 5, and to be hereinafter described, and against upward movement, because of the tension of a vertical coiled spring E⁵ at its opposite ends, connected to it and said frame D⁴, resting on the collar E, as above explained.

90 F is a vertical pulley-wheel on and located between the opposite end bearings of the

burnisher-shaft D², which is thereby or otherwise suitably confined against lengthwise movement through its bearings D³. F²F³ are two similar pulley-wheels arranged side by side and each carrying a similar and smaller pulley-wheel F⁴ F⁵. These wheels are severally arranged to turn in pairs on the rod D⁶; but each pair F² F⁴ and F³ F⁵ turns independently and separately from the other pair, and all are confined against endwise movement on said rod by the forked ends D⁵ of said frame D⁴. Each smaller pulley-wheel F⁴ F⁵ of the two pairs of pulley-wheels is connected by a belt, (not shown), so as to be driven in opposite directions, and the larger pulley-wheels F² F³ have a belt F⁶ to connect them, either one or the other, according as the belt is placed on one or the other, with the pulley-wheel F of the burnisher-shaft D², and thereby to rotate the burnisher, but in one direction when the belt F⁶ is on the pulley-wheel F² and in the other and opposite direction when said belt is on the other pulley-wheel F³, and the belt is automatically shifted from one pulley-wheel F² to the other F³, and vice versa, as will hereinafter appear.

The rod D⁶, having the frame D⁴, carrying the burnisher, swung on it, as explained, is extended from its said supports A⁵ toward the left of the bed, and its outer end portion D⁷ is screw-threaded and receives a screw-threaded collar G, having a hand-wheel G² for convenience in turning it, and thereby to adjust it lengthwise on said rod, for a purpose as will hereinafter appear. This collar G has a peripheral groove G³, which at opposite horizontal diametrical points is engaged by the upper fork-shaped end of a vertical lever-arm G⁴, which is hung on a fixed horizontal fulcrum pin or stud A⁹ of an upright A¹⁰ of the bed, and at its lower end is hung on a crank-pin G⁵ of a vertical disk G⁶, held on a horizontal shaft G⁷, turning at its opposite end portions in bearings of said upright A¹⁰ and of a companion upright A¹¹ of the bed, and between said uprights carrying a vertical ratchet-wheel G⁸.

G⁹ is a gravity-pawl to engage the teeth of the ratchet-wheel G⁸ at its upper side. This pawl G⁹ is fulcrumed on the upper end of a vertical arm G¹⁰, which intermediately of its length is fulcrumed on a shaft G⁷ and at its lower end is pivoted to one end of a horizontal arm G¹¹ and has the other end hung on a crank-pin G¹² at one end of a horizontal shaft G¹³, turning at its opposite end portions in bearing-blocks A¹² of the bed A, and at its end opposite to its end connected to arm G¹¹, as just stated, having a vertical bevel gear-wheel G¹⁴. The vertical planes of the shaft G¹³ of bevel gear-wheel G¹⁴ and the shaft G⁷ of the ratchet-wheel G⁸ are parallel and at right angles to the rod D⁶, on which is hung the frame D⁴, carrying the burnisher, and also at right angles to the axis of rotation of the burnisher D and the shaft C², carrying the boot or shoe heel.

H is a vertical bevel gear-wheel meshing with the vertical bevel gear-wheel G¹⁴, before referred to, and carried by a horizontal shaft H², turning at its opposite end portions in bearing-blocks A¹³ of the bed A, and having its axial line parallel with the axis of rotation of the burnisher D and of the shaft C².

H³ is a crank-arm at one end and the upper side of the shaft H², and H⁴ is a pitman-rod pivotally connected to said crank-arm and to the vertical lever-arm B⁹, by which the heel boot or shoe is oscillated, as has been explained, and intermediate of the fulcrum A³ of said lever B⁹ on the post A⁴ and the connection thereof with one end of the pitman-rod B⁸, and which at its opposite end is connected to the driving gear-wheel B⁴.

In the practical operation of the machine and under a continuous rotation of the driving-shaft B and through the mechanism connecting it and the frame D⁴, carrying the burnisher D, as has just been explained, the burnisher is moved rectilinearly to and fro in a line parallel to its axis of rotation, or, in other words, to and fro in a direct line across the edge and either from the treading-face of the heel toward the upper or vice versa. The mechanism directly securing this to-and-fro movement of the burnisher D consists of the rotating ratchet-wheel G⁸ and crank-connection with the fulcrumed arm G⁴, engaging the rod D⁶, on which the frame D⁴, carrying the burnisher, is hung. The ratchet-wheel is actuated or rotated by the pawl G⁹, which is moved forward, carrying the ratchet-wheel with it, and then backward over the wheel by the vibratory movement of the vertical lever-arm B⁹, acting through the mechanism described, and which connects said arm B⁹ with the vertical lever-arm G¹⁰, carrying the pawl G⁹. Further than the above, the coiled-spring connection E⁵ between the frame D⁴, carrying the burnisher D, and the handle-lever E³, with said lever secured as has been explained, gives the burnisher yielding and elastic pressure on the heel-edge which is being burnished by it, and also allows the burnisher to move within given limits outward and inward to accommodate itself to the varying distances of the edge of the heel from the axis of rotation of its carrying-shaft C² as the heel, because of being held on an offset of said shaft, revolves around its axis.

J is a radial or crank arm fixed on and projecting downward from the horizontal shaft H² and at the end opposite to its end connected, as described, to the driving gear-wheel B⁴.

J² is a pitman-rod at one end pivotally connected to crank-arm J and at the other end to a crank-arm J³, projecting from the under side of the collar J⁴, fixed on a horizontal shaft J⁵, having bearings at its opposite end portions in blocks A¹⁴ of the bed A. The collar J⁴ has a crank-arm J⁶ projecting from its upper side, and J⁷ is a gravity-pawl hung on said arm and in position to engage a ratchet-

wheel J^8 at its upper side. The ratchet-wheel J^8 turns on the horizontal shaft J^5 , and it has fixed to it a collar J^9 , provided at opposite diametrical points with two radial projecting fingers $J^{10} J^{10}$, in position as the collar and the ratchet-wheel are rotated to abut one after another against the upper side of a horizontal foot or treadle piece J^{11} of a vertical angular lever $J^{11} J^{12}$, fulcrumed at its angle J^{13} on a post A^{15} of the bed A. This angular lever $J^{11} J^{12}$ at the upper end of its vertical arm J^{12} has an under shoulder J^{18} for the rest and upward bearing of a latch-arm J^{14} of a horizontal lever J^{15} , fulcrumed at A^{16} on a post A^{17} of the bed, and its latch-arm J^{14} is connected by a vertical rod J^{16} with the handle-lever E^3 , which, as before explained, is connected to the frame D^4 , carrying the burnisher. Again, this horizontal lever J^{15} is extended into a position over the upper side of the loose and fixed pulley-wheels $B' B^2$ of driving-shaft B, and adapted (but which is not particularly shown, for the reason that it is well known) to act as a shipper to the driving-belt (not shown) of said pulleys, and thereby to move the belt from one pulley to the other by the swing of said lever J^{15} in either one or the other direction, and so place the machine, through its driving-shaft B, either into or out of connection with the driving-power used. With the catch-arm J^{14} of lever J^{15} engaged with the angular lever $J^{11} J^{12}$, as has been explained, the belt (not shown) for driving-shaft B is on the fixed pulley of said shaft, and with said catch-arm disengaged from the angular lever $J^{11} J^{12}$ said belt is on the loose pulley. Again, with the catch-arm J^{14} of lever J^{15} engaged with the angular lever $J^{11} J^{12}$ the handle-lever E^3 is also held fast, and the burnisher D is in its proper field of action and bearing on the edge of the heel of the boot or shoe held on the shaft C^2 , as explained, and it is also under the tension and elasticity of the spring E^5 , and with said catch-arm disengaged from the angular lever $J^{11} J^{12}$ the handle-lever J^3 and frame D^4 , carrying burnisher, are both free to swing upward from the reaction of the spring E^5 , and thereby the burnisher is placed out of its field of action and bearing on the edge of the heel held on the shaft C^2 . The angular lever is disengaged from the catch-arm J^{14} of the lever J^{15} twice in each rotation of the ratchet-wheel J^8 and by the operation of the finger-pieces J^{10} , carried by said ratchet, on the foot or treadle piece J^{11} of the angular lever $J^{11} J^{12}$, as has been hereinbefore more or less particularly alluded to. The angular lever $J^{11} J^{12}$ is automatically engaged with the catch-arm J^{14} of lever J^{15} by the action of a bent spring J^{17} , Fig. 5, properly applied to the lever, provided said catch-arm J^{14} is sufficiently depressed therefor, its said depression being conveniently secured by pressing or pulling down on the handle-lever E^3 . The ratchet-wheel J^8 makes one-half of a rotation during one half and remains stationary during the other half

of a complete rotation of the bevel gear-wheel H, and the collar J^4 , carrying the operating-pawl J^7 , and the shaft J^5 of said collar during the meantime vibrate in opposite directions—that is, forward and backward through one-half of a rotation. The vibratory shaft J^5 carries an arm K, projecting radially upward from it, and this arm at its upper end portion has two pins $K^2 K^3$ projecting horizontally from one face thereof.

K⁴ is a vertical rod passing, Fig. 3, between and upward above the pins $K^2 K^3$ of said arm K, and thence horizontally, as at K^5 , Figs. 1 and 2, and again vertically, as at K^6 , Figs. 2 and 3, directly through the thickness of the frame D^4 , carrying the burnisher, so as to turn at said vertical portion K^6 in said frame, but by collars $K^8 K^9$ above and below said frame D^4 and fixed on said rod K^6 to be held against vertical movement through the frame.

$K^{10} K^{11}$ are crank-arms both fixed on the vertical portion K^6 of the rod $K^4 K^5 K^6$, respectively above and below the frame D^4 , carrying the burnisher. Each crank-arm $K^{10} K^{11}$ at its outer end K^{12} , Figs. 1, 2, and 2^A, is of fork shape, and the fork of the upper crank-arm K^{10} , Figs. 2, 3, and 4, extends upward and that of the lower crank-arm K^{11} , Figs. 2^A, 3, 95 and 4, extends downward, and both are in position to embrace the width of the driving-belt F^6 for the pulley-wheel F of burnisher, and thereby under the swing of the vertical portion K^6 of the arm $K^4 K^5 K^6$ in one or the other direction on the frame D^4 to swing said crank-arms $K^{10} K^{11}$ in a direction either to move the belt from the pulley-wheel F^2 onto the pulley F^3 or from the pulley F^3 onto the pulley F^2 , as the case may be. The swing of the arm $K^4 K^5 K^6$, as has just been stated, is caused by the abutment of either pin $K^2 K^3$, carried by the shaft J^5 , as explained, against the vertical portion K^4 of said arm, and which portion K^4 , together with the horizontal portion K^5 , constitutes a crank-arm swinging by the vertical continuation K^6 thereof in the frame D^4 .

The mechanism just above described in the practical operation of the machine as a whole, and which operation is to be presently explained, secures the shifting of the belt F^6 from one pulley-wheel F^2 to the other pulley-wheel F^3 , or vice versa, and thus a reversing of the direction of rotation of the burnisher D, because of the opposite direction of rotation of the pulley-wheels $F^2 F^3$.

Further than as has been explained, the machine of this invention comprises a mechanism for withdrawing the spring-arm C^5 , confining, as explained, a boot or shoe at its heel in place for its edge to be burnished, and securing it out of and for setting said arm free to return to its operative position. This mechanism, Fig. 2, more particularly consists of a horizontal eye or staple L, held on and projecting from the right-hand vertical portion of the spring-arm C^5 , a vertical and angular catch-lever or hook $L^2 L^3$, Figs. 2, 2^A, and 3, to engage said eye, and a vertical bell-crank

arm or lever $L^4 L^7$, carrying said catch $L^2 L^3$ and adapted to be operated from a treadle-lever, (not shown,) and which is connected to it by a vertical rod L^6 . The catch L^2 5 L^3 is fulcrumed at its angle on the upper end of the vertical arm L^4 of the bell-crank and with its hook-arm L^2 uppermost and the open side of the hook toward the spring-arm C^5 and the other arm L^3 projecting horizontally 10 toward the right and at its outer end connected by a coiled spring L^8 to the bell-crank, and the bell-crank is fulcrumed at its angle L^5 on the upper end of a post or upright A^{18} of the bed A and has its arm L^7 horizontal 15 and extended toward the spring-arm C^5 , and at the outer end of said arm L^7 treadle-connection is made, as has been explained. Both the angular catch-lever and bell-crank at rest and in their normal position are vertical, and by pulling down on the treadle-connection rod L^6 the bell-crank, with its angular lever-catch, is carried toward and the catch-hook brought into engagement with the eye of the spring-arm C^5 , on which by the then 20 continued movement of the parts in the same direction the spring-arm C^5 , engaged with them, as stated, is pulled away from its operative position, to be there made fast, if so desired—as, for instance, by any suitable device (not shown) with which to fasten the bell-crank against its return from the reaction of a spring (not shown) suitably applied to it therefor.

The operation of the machine described and 25 as a whole is as follows: The boot or shoe which is to have the edge of its heel burnished (first, however, having, as hereinafter explained, drawn the spring or heel-clamping arm C^5 back by means of the lever-catch L^2 30 L^3 and its operating mechanism and, it being understood that the handle-lever E^3 is free and the burnisher out of operative position and the machine out of connection with the driving-power) is placed on and over the shaft 35 C^2 and the inner face of its sole at the heel against the end face C^4 of said shaft, and then the spring clamping-arm C^5 is released, and coming to a bearing against the treading-face of the heel the boot or shoe is thereby clamped 40 on the shaft C^5 with its edge to be burnished exposed. With the boot or shoe held as stated and the heel and the machine in its several parts properly adjusted, all as hereinafter particularly explained, and the burnisher under rotation in the proper direction, the handle-lever E^3 is then by the operator pulled down sufficiently to engage it with the catch-lever $J^{11} J^{12}$, which brings the rotating 45 burnisher against the heel-edge and connects 50 the driving-shaft B of the machine with the driving-power used, and thus, the machine being set in motion and the burnisher brought into contact with the edge of the heel, the heel is revolved first in one direction and then 55 in the other direction, carrying its edge forward and backward from one end to the other end of its breast under the burnisher, which

at the same time is moving inward and outward to suit the varying positions of the heel-edge relative to the axis of rotation 70 of the shaft C^2 , carrying the boot or shoe, also is bearing with an elastic and yielding pressure on the heel-edge, and is vibrating to and fro across the width of the edge of the heel between its treading-face and the upper, 75 and, furthermore, is changed in its direction of rotation when the heel is at either end of its said reciprocating revolution, and so on until from the continued running of the machine the lever-catch $J^{11} J^{12}$ is released from 80 its hold of the handle-lever E^3 by the operation thereon of one or the other, as the case may be, of the finger-pieces $J^{10} J^{10}$, carried by the rotating collar J^9 , whereupon the driving-belt (not shown) is shifted from the fixed to 85 the loose driving-pulley of the driving-shaft B , stopping the running of the machine and placing the burnisher out of operative position.

In the operation of the machine, as has been 90 explained, the oscillation of the segmental gear B^{10} secures, by the pitman-rod H^4 and crank-arm H^3 connection of it and of the horizontal shaft H^2 , a rock of said shaft H^2 , and thus, by the described connections of said 95 shaft and of the ratchet-wheels $G^8 J^8$, a step-by-step movement of each of said ratchets and a rock of the arm K . The step-by-step movement of the ratchet-wheel G^8 secures a vibratory movement of the burnisher across 100 the edge between the treading-face of the heel and the upper, and the step-by-step movement of the ratchet-wheel J^8 secures a release of lever-catch $J^{11} J^{12}$, and thereby a stop of the 105 running of the machine in all its parts, (excepting, however, as to the parts for rotating the burnisher,) and a placing of the burnisher from contact with the edge of the heel and the rocking of the arm K secures a shifting 110 of the driving-belt F^6 for the burnisher from 110 one to the other of the driving-pulleys F^2 F^3 . The operative parts are adjusted for a length of oscillation of the heel equal to the length of the edge of the heel from end to end of the breast thereof, also for the direction of rotation of the burnisher to be changed 115 at the end of each oscillation of the burnisher, and for a stop of the running of the machine and a placing of the burnisher out of contact with the edge of the heel, as has been stated, 120 on a given number of oscillations of the heel under the burnisher. The manner of making these several adjustments, it is believed, is obvious from the description already given without further particular explanation.

The parts of the machine for releasing the clamping-arm C^5 from the heel are worked by pulling the rod L^6 down, which swings the catch-hook $L^2 L^3$ over toward and engages it with the eye L of the clamping-arm C^5 , so that 130 on the continued downward pull on said rod said arm is drawn backward, releasing the boot or shoe for its removal from and for the placing of another heel on the machine, on

which, releasing the rod L^6 , the clamping-arm C^5 is left free to clamp the boot or shoe, as before, and the catch-hook L^2 L^3 to disengage from it and to return with all connecting parts to its and their normal positions, Fig. 2.

As particularly shown and described, the machine is stopped twice for each rotation of the disk or collar J^9 , carrying the finger-pieces J^{10} , and, as is plain, with a single finger-piece the machine would then be stopped once only for each rotation of said disk or collar, and with three or more finger-pieces, at equal or unequal distances apart the machine would then be stopped three or more times, according to the number of finger-pieces for each rotation of said disk or collar.

The rod D^6 , through which, as has been described, the carrier D^4 for the burnisher is moved to and fro, is in separate lengthwise-telescoping parts D^7 D^8 , Figs. 1 and 2, and the part D^8 and upper forked end of lever-arm G^4 , engaging screw-nut G , are connected by a rod D^9 , that at its opposite ends is pivoted to the part D^8 and arm G^4 , all so that by suitably turning the screw-nut the part D^8 is moved either in or out, as the case may be, on the part D^7 , shortening or lengthening the rod D^6 as a whole, and thereby to adjust the burnisher and to insure its movement to and fro across the edge of the heel between the treading-face thereof and the upper and fully to the upper, and also to center the belt-shifting device described relative to the driving pulley-wheels F^2 F^3 for the burnisher.

Having thus described my invention, what I claim, and desire to secure by Letters Patent, is—

1. In a machine for burnishing the edges of heels of boots and shoes, a shaft C^2 , suitably supported, having an offset heel-rest C^4 and an arm C^5 for clamping a boot or shoe at its heel on said rest, in combination with means for oscillating said shaft, substantially as described, for the purposes specified.

2. In a machine for burnishing the edges of heels of boots and shoes, in combination, a shaft C^2 , suitably supported, having a heel-rest and an appliance for clamping a boot or shoe at its heel on said rest, means for oscillating said shaft, a burnisher, a frame D^4 , carrying the burnisher at one end, a horizontal support D^6 , having the end of frame D^4 opposite to that carrying the burnisher hung on it so as to both swing vertically and to move rectilinearly horizontally to and fro across its vertical plane of swing, means for moving frame D^4 to and fro on its support D^6 , a vertical spring E^5 at its upper end, secured to frame D^4 between the burnisher and support D^6 , and a horizontal lever E^3 , fulcrumed on a suitable support and having the lower end of spring E^5 secured to it.

3. In a machine for burnishing the edges of heels of boots and shoes, in combination, a shaft C^2 , having a heel-rest and an appliance for clamping a boot or shoe at its heel on said rest, means for oscillating said shaft, a rotat-

ing burnisher, a carrier D^4 , suitably supported, for said burnisher, driving pulley-wheels F^2 F^3 of said burnisher-carrier, and each pulley-wheel arranged to be separately driven, a belt F^6 , for connecting said pulleys with a pulley-wheel F of the burnisher, a belt-shifting device K^4 K^5 K^6 K^{10} K^{11} of the burnisher-carrier D^4 , and means for moving said belt-shifter to and fro on said carrier D^4 and thereby to shift the belt F^6 from one to the other of said pulley-wheels F^2 F^3 , substantially as described, and for the purposes specified.

4. In a machine for burnishing the edges of heels of boots and shoes, in combination, a shaft C^2 , suitably supported, having a heel-rest C^4 and an arm C^5 to clamp a boot or shoe at its heel on said rest, means for rotating said shaft, and appliances for placing said arm out of clamping position, consisting, essentially, of an eye L on the arm C^5 , a vertical hook-lever L^2 L^3 , and a vertical bell-crank lever L^4 L^7 , suitably supported and having said hook-lever L^2 L^3 fulcrumed on and the arm L^3 of said hook-lever connected by a spring L^8 to its arm L^7 , substantially as described, for the purposes specified.

5. In a machine for burnishing the edges of heels of boots and shoes, a shaft C^2 , suitably supported, having a heel-rest and an appliance for clamping a boot or shoe at its heel on said rest, a pinion gear-wheel C of said shaft C^2 , a segmental gear B^{10} , meshing said pinion and at one end of a lever-arm B^9 fulcrumed at A^3 , in combination with a rotating wheel B^4 , having radial slot B^5 , and a pitman-rod B^8 at one end jointed in said slot B^5 of and secured to said wheel B^4 and at the other end jointed to said lever-arm, substantially as described, for the purpose specified.

6. In a machine for burnishing the edges of heels of boots and shoes, a shaft C^2 , suitably supported, having a heel-rest and an appliance for clamping a boot or shoe at its heel on said rest, means for oscillating said shaft, a burnisher, a carrier D^4 for said burnisher, adapted to be moved to and fro on a suitable support, means for moving said burnisher-carrier to and fro on its said support, consisting, essentially, of a vertical fulcrumed lever-arm G^4 , engaged with said carrier, a crank G^5 , held on a rotating shaft G^7 and connected to said lever-arm, a ratchet-wheel G^8 , held on said shaft, a pawl G^9 , for engaging said ratchet-wheel, a lever-arm G^{10} , carrying said pawl and fulcrumed on said shaft, a shaft G^{13} , means to rock shaft G^{13} , and a pitman-rod G^{11} , connecting said rocker-shaft and said lever-carrying pawl, substantially as described, for the purpose specified.

7. In a machine for burnishing the edges of heels of boots and shoes, a shaft C^2 , suitably supported, having a heel-rest and an appliance for clamping a boot or shoe at its heel on said rest, means for oscillating said shaft, a rotating burnisher, a carrier D^4 , suitably supported, for said burnisher, driving pulley-

wheels F^2 F^3 of said burnisher-carrier and each pulley-wheel arranged to be separately driven, a belt F^6 , for connecting said pulleys with pulley-wheel F of the burnisher, a belt-shifting device K^4 K^5 K^6 K^{10} K^{11} of the burnisher-carrier D^4 , and means for moving said belt-shifter to and fro on said carrier D^4 and thereby to shift the belt F^6 from one to the other of said pulley-wheels F^2 F^3 , and which consist, essentially, of an arm K , having pins K^2 K^3 at opposite points to abut against the arm K^4 of said belt-shifter, a shaft J^5 , on which said arm is held, and means to rock said shaft and its said arm to and fro, substantially as described, for the purposes specified.

8. In a machine for burnishing the edges of heels of boots and shoes, in combination, a shaft C^2 , suitably supported, having a heel-rest and an appliance for clamping a boot or shoe at its heel on said rest, means for oscillating said shaft, a burnisher, a carrier D^4 , suitably supported, for said burnisher and adapted to be moved to and fro on said support and to exert an elastic and yielding pressure of the burnisher on the edge of the heel being burnished and to allow the burnisher to move outward and inward with the heel, means for moving the burnisher-carrier D^4 to and fro on its support, a belt F^6 , for rotating said burnisher, pulley-wheels F^2 F^3 , held on said carrier D^4 , for driving said belt F^6 , and means for shifting said driving-belt from one to the other of said driving-pulleys, substantially as described, for the purposes specified.

9. A machine for burnishing the edges of heels of boots and shoes, consisting, essentially, of a shaft C^2 , suitably supported, having an offset heel-rest C^4 and an appliance for clamping the heel of a boot or shoe on said rest, means for oscillating said shaft C^2 , a rotating burnisher, a carrier D^4 , suitably supported, for said burnisher and adapted to be moved to and fro on said support and to exert an elastic and yielding pressure of the burnisher on the edge of the heel being burnished and to allow the burnisher to move outward and inward with the heel, means for moving the burnisher-carrier D^4 to and fro on its support, a belt F^6 , for rotating said burnisher, pulley-wheels F^2 F^3 , held on said carrier D^4 , for driving said belt F^6 , and means for shifting said driving-belt from one to the other of said driving-pulleys, substantially as described, for the purposes specified.

10. In a machine for burnishing the edges of heels of boots and shoes, in combination, a rotating burnisher, means for rotating the burnisher, and a carrier D^4 for the burnisher and its said means for rotating it, composed in one part of a longitudinal telescoping rod D^6 , arranged to move to and fro on a suitable support, a screw-threaded nut G on part D^7 of rod D^6 , means engaging said screw-nut for moving through it and rod D^6 the burnisher-carrier D^4 to and fro on its support, and a rod D^9 at opposite ends held on said means engaging the screw-nut and on part D^8 of rod D^6 , substantially as described, for the purposes specified.

In testimony whereof I have hereunto set my hand in the presence of two subscribing witnesses.

WINSLOW F. SAMPSON.

Witnesses:

ALBERT W. BROWN,
EDWARD HAMILTON.
